US0D1030347S

(12) **United States Design Patent** (10) **Patent No.:** **US D1,030,347 S**
(45) **Date of Patent:** **** Jun. 11, 2024**

(54) **BAG RACK**

(71) Applicant: **Inno-Pak, LLC**, Delaware, OH (US)

(72) Inventors: **Jonathan D. Sill**, Delaware, OH (US);
Christopher T. Sill, Westerville, OH (US)

(73) Assignee: **Inno-Pak, LLC**, Delaware, OH (US)

(**) Term: **15 Years**

(21) Appl. No.: **29/928,253**

(22) Filed: **Feb. 9, 2024**

Related U.S. Application Data

(62) Division of application No. 29/904,625, filed on Oct. 10, 2023, which is a division of application No. 29/883,799, filed on Feb. 3, 2023, now Pat. No. Des. 1,006,480, which is a division of application No. 29/717,361, filed on Dec. 17, 2019, now Pat. No. Des. 993,657.

(57) **CLAIM**

The ornamental design for a bag rack, as shown and described.

DESCRIPTION

FIG. 1 is a perspective view of a bag rack showing a new design;

FIG. 2 is a left side elevation view thereof, the right side being a mirror image;

FIG. 3 is a rear elevation view thereof;

FIG. 4 is a front elevation view thereof;

FIG. 5 is a top plan view thereof;

FIG. 6 is a bottom plan view thereof; and,

FIG. 7 is front perspective view thereof, showing the bag rack with a plurality of bags thereon and showing a bag in an open configuration.

The dashed lines shown in the drawings are for environmental purposes only and form no part of the claimed design.

1 Claim, 7 Drawing Sheets
